Patented Sept. 14, 1920.

UNITED STATES PATENT OFFICE.

EMIL JACOBSEN, OF EVANSTON, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,352,605.

Specification of Letters Patent. Patented Sept. 14, 1920.

Application filed July 1, 1918. Serial No. 242,749.

To all whom it may concern:

Be it known that I, EMIL JACOBSEN, a citizen of the United States of America, and a resident of Evanston, in the county of 5 Cook and State of Illinois, have invented certain new and useful Improvements in Automatic Telephone Systems, of which the following is a specification.

My invention relates in general to an 10 automatic telephone system and more particularly to an improved automatic switch of the type known as a selector switch, that is, one which has access to a plurality of trunk lines divided into groups and which 15 may be numerically operated to select a desired group of trunk lines and will then operate automatically to select an idle trunk line in that group and extend a connection thereto.

20 In the past a selector switch of the standard type has been given access to ten trunk lines in a group or level, that is, it might step ten times automatically over a level of ten trunks, and if more trunk lines were 25 desired in a group, then the switch must take more than ten steps, which operation would require too great an expenditure of time.

The object of my invention is to provide 30 such a selector switch which has a double set of wipers and a double bank of contacts associated therewith, together with means for causing the selector, after both sets of wipers have been raised to a certain level, 35 to test two trunks at each rotary step, so that twenty trunks may be tested in search of an idle one in the same time previously taken to test ten trunks, that is, the first trunk in the level associated with the one 40 set of wipers is first tested. If that is busy the corresponding trunk in the upper bank, associated with the other set of wipers, is then tested, and if both are busy the switch is rotated so that the next pair of trunks 45 may be tested.

I will now describe the operation of the switch in detail by referring to the accompanying drawing in which I have shown a calling subscriber A having a rotary line 50 switch C of a well known rotary type individual to his line, which is operated to select an idle one of a number of first selectors, one of which is shown at E and which selector E is of the well known type of Keith Erickson switch of the side switchless type with

the addition of certain circuits which adapt it to operate in accordance with the features of my invention.

When the subscriber at substation A moves his receiver a circuit is closed by the 60 switch hook springs for the line relay 2 of the rotary line switch C in series with the line circuit. Relay 2 operates in the usual manner to close a circuit at springs 3 for relay 4 and magnet 6 in series and to at the 65 same time close a circuit from magnet 6 directly to the private wiper 9 through springs 10 and 11. Therefore if the trunk line upon which the wipers 7, 8 and 9 rest is busy, a ground from said wiper 9 will 70 short circuit the relay 4 before it may operate, and will cause rotary magnet 6 to operate to step the said wipers to an idle trunk line. When such idle trunk line is reached the relay 4 energizes in series with the ro- 75 tary magnet 6, as it is no longer shorted out by ground on wiper 9. Relay 4, upon energizing, disconnects relay 2 and ground from the line circuit of substation A and connects said line through its front contacts to the 80 line wipers 7 and 8 which it will be assumed now rest in engagement with contacts connected to the idle selector switch E.

At this time a circuit is closed for the line relay 12 of selector E from ground, 85 through winding 13 of an induction coil off normal springs 14, lower winding of said relay, springs 15 and 16, springs 17 and 18, wiper 8, to and through the apparatus of substation A, and back through wiper 7, 90 springs 19 and 20, springs 21 and 22, and upper winding of said relay to battery. Relay 12 energizes at this time, and closes a circuit for relay 23 from ground through springs 24, springs 25, springs 26 and 27, 95 and said relay to battery. Relay 23 operates to prepare a circuit at springs 28 and 29 for the vertical magnet 30 and relay 31, and also supplies a holding ground to the relay 4 of line switch C from ground 100 through springs 32, wiper 9, and through said relay 4 and magnet 6 to battery.

The calling device may now be operated to send a series of impulses corresponding to the first digit of the called number, at which 105 time relay 12 operates in accordance therewith to close the circuit of the magnet 30 and relay 31 through the back contact of relay 12 and front contacts of relay 23. Magnet 30 now operates to step the wipers 110

33-38 inclusive to some level of the banks from which trunk lines lead to the desired exchange or to switches of any desired type. It is to be understood that the wipers 33, 34 and 35 are the line and private wipers of one set, and have access to one bank of one hundred contacts, while wipers 36, 37 and 38 are the line and private wipers of another set and have access to a separate bank of one hundred contacts, and that both sets of wipers are mounted upon the same shaft and move together. Relay 31 which is energized during the operation of magnet 30 closes a circuit at springs 39 and 40 extending from ground springs 32, springs 41, off normal springs 42, springs 40 and 39 and lower winding of relay 43 to battery. Another branch of this circuit extends from spring 40 through spring 44 and upper winding of relay 43 to battery. Relay 43 is so constructed that it will energize only with both windings energized fully and not with either winding alone. Also neither winding will be fully energized if either of relays 45 or 46 are in series therewith. At the same time a circuit is closed from ground through springs 32, springs 41, springs 47, winding of relay 46, and upper winding of relay 43 to battery, and another over the same path, through springs 48, relay 45, and lower winding of relay 43 to battery. Relays 45 and 46 are however short circuited at this time by the direct ground circuit through springs 39, 40 and 44, so that only relay 43 energizes. Relay 43, upon energizing, prepares a circuit at springs 49 for the rotary magnet 50, and closes a locking circuit for itself through springs 24 and 25 of relays 45 and 46. As soon as relay 31 falls back the circuit of the rotary magnet is completed at springs 51 and 40 so that magnet 50 operates to step the wipers 33, 34, 35 and 36, 37 and 38 onto the first set of contacts of their respective banks. Assume now that the trunks connected to the contacts with which both sets of wipers engage are both idle, and no ground is therefore connected to wipers 35 and 38. Then as magnet 50 energizes and opens the circuit of relay 43, said relay deenergizes to open the circuit of magnet 50 in turn. As magnet 50 deenergizes it again supplies battery to the windings of relay 43. In this instance however, relays 45 and 46 are no longer short circuited by relay 31, and relays 45 and 46 both energize over the previously traced circuit in series with the windings of relay 43, which relay 43 however does not energize at this time. Relays 45 and 46 are so arranged that each opens the circuit of the other at either springs 47 or 48 so that only one of said relays will remain energized. Suppose that relay 45 energizes a second earlier than 46, then relay 46 will be cut off at springs 47, while relay 45 will energize to disconnect the line relay 12 from the line circuit, connect the line circuit to wipers 23 and 24, disconnect ground from the line relay springs at springs 24, and prepare a locking circuit for itself at springs 52 and 53 extending to wiper 35 which is supplied with a holding ground from the switch ahead in the usual manner as soon as the line relay thereof energizes. It will be seen therefore that if both of the first pair of trunk lines tested in a level are idle, the switch will cut through to one or the other of said lines depending upon which relay 45 or 46 energizes first.

Now if the trunk line which the wipers 36, 37 and 38 test is busy the operation will be the same as above except that the ground on wiper 38 will maintain the relay 46 short circuited, so that it cannot energize, and relay 45 will cut through. Suppose the trunk line with which the wipers 33, 34 and 35 connect is busy, then there will be a ground present at wiper 35 which will short circuit the winding of relay 45 from said wiper 35, springs 52 and 54, and lower winding of relay 43 to battery. In this case relay 45 cannot energize, but relay 46 being no longer shorted out, energizes to switch the line circuit to the wipers 36 and 37, disconnect the line relay 12 and ground at springs 25, and also closes a locking circuit for itself extending through springs 55 and 56 and to the private wiper 38, which is also supplied with a holding ground from the switch ahead.

Now let us assume that both trunk lines tested at this time are busy, then there will be a guarding ground potential on the contacts tested by both the wipers 35 and 38. In this case both of the relays 45 and 46 will be short circuited by this ground and relay 43 will have a direct circuit to ground through both its windings and the said private wipers. Relay 43 will therefore energize to again close a circuit for the rotary magnet at springs 49 so that the wipers 33-38 inclusive, will be moved one step onto the next pair of contacts leading to the next pair of trunk lines. The same cycle of operations are now again carried on, that is, if either of these trunks are idle the line circuit will be switched to that trunk line, while if both are busy the switch will rotate until an idle trunk or pair of trunks is located.

In the drawing I have shown the lower winding of the line relay 12 connected to ground through the secondary of an induction coil 13. The secondary of this coil is connected from ground through condenser 57, and resistance 58 to battery. The interrupter relay 59 is arranged so that it intermittently supplies ground to the junction of the resistance 58 and condenser 57 so that this condenser is charged and dis-

charged intermittently to produce a low so called trunk tone in the secondary of said induction coil. The purpose of this tone is as follows: When the subscriber lifts his receiver and operates the calling device for the first digit, he may listen after the transmission of this digit until this trunk tone ceases, that is, until one of the relays 45 and 46 energizes to disconnect the line relay 12 from the line circuit. This will of course inform him that an idle trunk line has been seized by his first selector and he may proceed with the call.

Suppose that the twenty trunks in a level are all busy so that the switch operates to the last trunk and then takes another step and the off normal springs 41, 14 and 60 are operated by the shaft, then the busy machine M will be connected in series with the line relay 12 and the calling line through springs 60 to notify the calling man that all the trunks are busy, the springs 41 will be opened to prevent the energization of relays 45 or 46, and springs 14 will be opened to disconnect the trunk tone apparatus from the line relay.

It will be seen therefore that I have provided a very efficient type of automatic selector switch which will test 200 trunks in the same time now taken to test 100 trunks, and without the switch being required to take more than ten steps.

Having fully described and ascertained the features of my invention, what I consider to be new and desire to have protected by Letters Patent will be pointed out in the appended claims.

What I claim as my invention is:

1. In a telephone system, a line, an automatic switch for said line having a plurality of sets of wipers, trunk lines accessible to each set of wipers, means for making any of said trunk lines busy, means for causing said switch to test a pair of said trunk lines simultaneously, and if one of the tested trunk lines is busy for extending a connection from said line over the idle trunk.

2. In a telephone system, a line, an automatic switch for said line having a plurality of sets of wipers, normally idle trunk lines accessible to each set of wipers, means for making any of said trunk lines busy, means for causing said switch to test a pair of said trunk lines simultaneously, and if both of the tested trunks are busy for causing the switch to test another pair of said trunk lines.

3. In a telephone system, a line, an automatic switch for said line having a plurality of sets of wipers, trunk lines accessible to each set of wipers, means for making any of said trunk lines busy, means for causing said switch to test a pair of said trunk lines simultaneously, and if both of the tested

trunks are busy for causing the switch to test another pair of said trunk lines, and if one of the said last mentioned trunks are idle, for extending a connection from the line over the idle trunk.

4. In a telephone system, a line, an automatic switch for said line having a plurality of sets of wipers, trunk lines accessible to each set of wipers, means for making any of the said trunk lines busy, means for causing said switch to test a plurality of trunk lines simultaneously one for each set of wipers, and if any of said trunk lines are idle, for extending a connection from said line via said wiper to the idle one of said trunk lines.

5. In a telephone system, a line, an automatic switch for the line having a plurality of sets of wipers, trunk lines accessible to said wipers, means for making any of said trunk lines busy, means for causing said switch to test a plurality of said trunk lines simultaneously through the medium of said wipers, said means comprising a test relay common to said sets of wipers, for continuing the operation of the switch when all the tested trunks are busy, and a switching relay for each set of wipers for extending a connection over its associated set of wipers when the trunk line tested thereby is idle.

6. In a telephone system, a line, an automatic switch for said line for extending connections therefrom having a plurality of wiper sets, groups of trunk lines accessible to said wipers, means for making any of said trunk lines busy, a line relay for said automatic switch controlled over said line by impulses corresponding to a digit of a called number to cause said switch to bring each wiper set opposite a desired group of trunk lines, and automatic means for then causing said switch to test a plurality of said trunk lines simultaneously.

7. In a telephone system, a line, an automatic switch for said line for extending connections therefrom having a plurality of wiper sets, groups of trunk lines accessible to said wipers, means for making any of said trunk lines busy, a line relay for said automatic switch controlled over said line by impulses corresponding to a digit of a called number to cause said switch to bring each wiper set opposite a desired group of trunk lines, and automatic means for then causing said switch to test a plurality of said trunk lines simultaneously, and if any of the trunk lines are idle for causing the switch to extend a connection from the line over one of the wiper sets to an idle trunk.

8. In a telephone system, a line, an automatic switch for said line for extending connections therefrom having a plurality of wiper sets, groups of trunk lines accessible to said wipers, means for making any of said trunk lines busy, a line relay for said auto-

matic switch controlled over said line by impulses corresponding to a digit of a called number to cause said switch to bring each wiper set opposite a desired group of trunk lines, and automatic means for then causing said switch to test a plurality of said trunk lines simultaneously, and if any of the trunk lines are idle for causing the switch to extend a connection from the line over one of the wiper sets to an idle trunk, and if all of the tested trunks are busy, for causing the switch to test another plurality of said trunk lines simultaneously.

9. In a telephone system, a calling line, a directly controlled automatic switch for said line controlled thereover in response to impulses of a digit of a called number, trunk lines accessible to said switch, a plurality of other similar switches having access to said trunk lines and adapted to make any of said trunk lines busy to calls from said first switch, said first switch adapted to move in one direction to pick out a group of said trunk lines in response to said impulses, and automatic means for causing said switch to move in another direction to test the trunk lines of a group two at a time and stop and extend a connection over the first one of said trunk lines which has not been seized by one of said other switches.

10. In a telephone system, a calling line, an automatic switch having vertical and rotary movement, means for extending a talking circuit from said line to said automatic switch, a plurality of trunk lines accessible to said switch, means controlled from said calling line over the extended talking circuit for causing said switch to rotate and then simultaneously test a pair of said trunk lines, and means in said switch to extend a connection over the first idle one of said trunk lines.

11. In a telephone system, a calling line, two groups of trunk lines, two serially related forward selecting automatic switches for connecting the calling line with one of said trunk lines which is not in use, and testing means in the second of said switches for testing trunk lines in both of said groups simultaneously.

12. In a telephone system, a calling line, an automatic selector switch, an individual line switch for extending the calling line to said selector switch, two groups of trunk lines accessible to said selector switch, means whereby the subscriber on the calling line can start the operation of said selector switch to connect with an idle trunk line, and means in said selector switch for testing trunk lines in both of said groups simultaneously.

13. In a telephone system, a calling line, a plurality of trunk lines, an automatic switch for connecting said calling line with one of said trunk lines, and testing means in

said switch for locating a trunk line not in use, said testing means comprising two test wipers and a common test relay with circuit connections for testing two of said trunk lines simultaneously.

14. In a telephone system, a calling line, groups of trunk lines, an automatic switch having primary group selecting movement and automatic secondary trunk selecting movement, means whereby the subscriber on said line can directly control said switch in its primary movement to select a desired group of said trunk lines, means for initiating the secondary movement of said switch at the end of the primary movement to locate an idle trunk line, and a plurality of testing means in said switch for testing a corresponding plurality of trunk lines in the selected group simultaneously.

15. In a telephone system, a directly controllable automatic selector switch for connecting a calling and called line, two groups of trunk lines available for establishing the connection, means in said switch for selecting an idle trunk in either group, two switching relays for closing the connection through said switch, and means for operating one or the other of said relays depending on the group in which the selected trunk is located.

16. In a telephone system, a calling line, a plurality of trunk lines, means comprising an automatic switch for connecting said calling line with one of said trunk lines, testing means including two test wipers for testing said trunk lines to locate an idle trunk line, a switching relay associated with each test wiper, circuit connections for maintaining said relays short-circuited while the test wipers are passing over busy trunk lines, and means for energizing one of said relays when its associated test wiper finds an idle trunk line.

17. In a telephone system, a trunk line terminating in an automatic switch, two sets of wipers for said switch, groups of trunk lines accessible to said wipers, means for directly controlling said switch over said first trunk line to cause said wiper sets to select two of said trunk groups, means for causing a secondary movement of said switch, testing means effective during the secondary movement to test the trunk lines in both of the selected trunk groups to select an idle trunk line, two switching relays for connecting said first trunk line with said wiper sets, respectively, and means effective when an idle trunk line is found for operating one of said relays without operating the other, the relay operated depending on the group in which the selected trunk line is located.

Signed by me at Chicago, Illinois, this 24th day of June, 1918.

EMIL JACOBSEN.
